W. J. Anderson,
Attorney.

UNITED STATES PATENT OFFICE.

JOHN R. CAMPBELL, OF AUSTIN, TEXAS.

AEROPLANE.

1,229,410.

Specification of Letters Patent. Patented June 12, 1917.

Application filed January 4, 1916. Serial No. 70,134.

To all whom it may concern:

Be it known that I, JOHN R. CAMPBELL, a citizen of the United States, residing at Austin, in the county of Travis and State of Texas, have invented certain new and useful Improvements in Aeroplanes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to improvements in aeroplanes and more particularly to their means of propulsion.

The invention proposes a novel organization of front and rear propellers and supporting planes with means for distributing and controlling the air currents developed by the action of the propellers whereby the head on resistance to flight is reduced and the developed air currents are caused to co-act with the planes, and in such co-action may be variously utilized, to promote the stability of the machine, to provide for ease and facility in landing and to enable the speed of flight to be regulated as desired, independently of the speed of the engine and of the propeller shafts.

An embodiment of the invention is illustrated in the accompanying drawings wherein:

Figure 1 is a plan view of an aeroplane in which the features of the invention are incorporated, portions of the planes being broken away to expose to view the underlying parts.

Fig. 2 is a side elevation thereof.

Fig. 3 is a front elevation thereof.

Fig. 4 is a detail sectional view showing the air conduits which form the framing of the planes and one of the deflectors which are combined with said conduits.

Fig. 5 is a bottom plan view of the deflector shown in Fig. 4.

Fig. 6 is a detail sectional view showing a valve for controlling the co-action of the air currents with the planes.

Similar characters of reference designate corresponding parts throughout the several views.

The invention is not concerned with the construction of the body of the aeroplane nor with any particular arrangement of its

planes. As shown, the body 1 resembles the hull of a boat and is equipped with a pair of planes 2, one at each side thereof.

The driving equipment of the machine includes a front propeller 3 and a rear propeller 4 mounted on shafts 5 and 6 respectively and driven from an engine 7 which is suitably located in the body or hull 1. The shaft 6 has combined therewith a manually controlled reversing gear system 8 of any suitable construction which is shown merely diagrammatically in the drawings and by which the direction of rotation of the rear propeller 4 may be reversed when desired for purposes to be hereafter set forth.

The propellers 3 and 4 are located symmetrically of the bow and stern of the hull 1 and rotate within casings 9 and 10 respectively. The casing 9 is preferably in the form of a truncated cone, its wider end adjoining the planes 2. The casing 9 serves as a deflector or distributor for the air currents developed by the action of the propeller 3, directing these currents rearwardly in concentrated volume.

The invention effects the correlation of the operations of the propellers 3 and 4 and the co-action of the air currents developed by said propellers with the planes 2 and proposes means for enabling such co-action to be utilized for the various purposes above stated. These results are achieved by a system of distributing and controlling the said air currents, which, as shown, includes air trunks 11 located at each side of the hull 1 and a system of air conduits or tubes extending under and preferably forming a part of, each plane 2.

The air trunks 11 are connected at their rear ends to the casing 10 which incloses the propeller 4 and terminate at their front ends adjacent the rear end of the casing 9 which incloses the propeller 3. The air trunks may be formed as ordinary cylindrical pipes but in the embodiment disclosed they are substantially semi-circular in cross section and are applied to the body 1 in such manner that the sides of said body form parts of the walls of said trunks.

The air conduit system includes connected transverse and longitudinal tubes 12 and 13 which communicate at their intersections and are preferably utilized as the framing of the planes 2. The tube framings 12-13 are supported in any suitable way at each side of the body 1 and their inner longi-

tudinal bars 13 are connected by flexible piping 14 or otherwise to the trunks 11.

The tube framings 12—13 are open to the atmosphere at regular intervals. For this purpose openings 15 (see Fig. 4) are provided which are preferably located at the intersections of certain of the tubes 12 and 13 and at the upper sides thereof. As shown, the openings 15 are provided at the intersections of the several intermediate tubes and there are nine of these openings for each plane.

It is preferred to combine with each opening 15 a deflector 16 which projects forwardly along a line directed toward the vertical diameter of the casing 9. Each deflector 16 has a downwardly facing convex side and tapers uniformly from its center toward each end. Its inner end is formed 20 as a lip 17 which is attached in any suitable manner to the tube framing and extends over the opening 15 to direct currents of air into or from said opening.

The piping 14 which connects each tube framing 12—13 and the adjacent trunk 11 communicates at its lower end with a valve box 18 formed as a part of said trunk. This valve box incloses valves 19 and 20 which are operated by suitable lever systems 21 arranged within the body 1. The valve 19 is operative when in a vertical position to cut off the portion of the trunk 11 in front of the valve box 18 from the portion of said trunk in the rear of said valve box and also 30 from the tube framing 12—13 or when in a horizontal position to cut off the trunk as an entirety from said tube framing while establishing the communication of its said front and rear portions with one another. The valve 20 is operative independently of the valve 19 to cut off the tube framing 12—13 from the trunk 11. Thus in any position of the valve 19 except its horizontal position the trunk 11 and the tube framing 12—13 will be in communication through the piping 18, providing the valve 20 is in an open position.

The casing 9 is open at both ends and projects laterally for some distance beyond each trunk 11 whereby the air currents developed by the action of the propeller 3 will be directed rearwardly in part through the trunks 11 and in part under the planes 2. The casing 10 is open at its rear end and forms, in effect, a common continuation of the trunks 11. In normal flight the valve 19 which is not unlike a damper is positioned to enable air to pass more or less freely from one end of each trunk 11 to the other and both propellers rotate in the same direction. In this way the rear propeller sets up a suction influence of more or less intensity in the trunks 11, the effect of which is to relieve or reduce the air pressure behind the front propeller whereby the

latter develops an augmented suction influence immediately in front of the machine and the head on resistance to flight is materially reduced. The movements of the air currents under normal conditions are indicated by arrows in Fig. 1.

The rear propeller is also utilized in the stabilizing of the machine. For this purpose the tube framings 12—13 are normally in communication of greater or less degree with the trunks 11 and hence are subject to the suction influence developed in said trunks by the action of the rear propeller. It follows from this that the air currents directed by the casing 9 under the planes 2 will be induced in greater or less degree through the openings 15 and as these air currents pass in relation to the deflectors 16 they produce an accumulated pressure effect under the planes 2 with a consequent development of a sensible lifting or supporting force and a general stabilizing of the machine. When it happens that the pressure on one of the acting surfaces or planes is greater than on the other one so that the machine tends to list or tilt such difference in pressure may be compensated for and the equilibrium of the machine instantly restored by relative operations of the valves 20, *i. e.*, by operating the valve 90 adjoining the plane subject to the lesser pressure to provide for a greater pressure accumulation under said plane or by operating the other valve to provide for a less pressure accumulation under the other plane 100 or by operating both valves simultaneously in the respective ways suggested.

When making a landing the valves 19 are moved to vertical positions and the rear propeller 4 is reversed by an appropriate manipulation of the gearing 8. The reversal of the rear propeller owing to its smaller size and power capacity, does not arrest the flight of the machine although it obviously materially reduces the speed of flight as the machine approaches the landing station. At the same time the rear propeller, in its reversed rotation, forces relatively strong air currents forwardly through the trunks 11. These air currents are intercepted by the vertically disposed valves 19 and are caused to flow into the tube framings 12—13 from which they issue with considerable intensity at the openings 15. The effect of these air currents escaping from the openings 15 in relation to the deflectors 16 is to build up under the planes a cushion of air which enables the landing of the machine with ease and without sensible shock.

In starting a normal elevation for flight 125 may be very quickly attained by utilizing the lifting effects of the air currents passing from the openings 15 and in relation to the deflectors 16. For this purpose the valves 19 are angularly disposed, the valves 130

20 are opened, the front propeller is rotated forwardly and the rear propeller is in reverse rotation. This causes the air currents to pass from the openings 15 and under the 5 planes with augmented volume and intensity. The speed of flight may be effectively regulated by reducing or stopping the rotation of the rear propeller and a very low speed, as in circling, may be secured by 10 reversing the rear propeller and utilizing for the forward movement of the machine only the tractive effect of the front propeller. The speed of flight may also be regulated though within a reduced range, by 15 positioning the valves 19 to cut off, more or less, the portions of the trunks 11 in front of the boxes 18 from the portions of said trunks in the rear of said boxes, the speed being retarded as the communication 20 of the front and rear portions of the trunks 11 is reduced.

A fan shaped plane 21 for elevating and lowering, and a triangular shaped vane 22 for steering, of any approved type and operable in the usual manner, may be employed.

Having fully described my invention I claim:

1. An aeroplane having in combination front and rear propellers, lateral planes, a 30 casing surrounding the rear propeller and a system of air conduits associated with each plane, open to the atmosphere at various points under the plane and connected to said casing for communication therewith.

2. An aeroplane having in combination front and rear propellers, lateral planes, a casing surrounding the rear propeller, air trunk means extending from a point in the rear of the front propeller to said casing and 40 communicating therewith, and a system of air conduits associated with each plane, open to the atmosphere at various points under the plane and connected to said air trunk means for communication therewith.

3. An aeroplane having in combination front and rear propellers, lateral planes, an open-ended casing surrounding the front propeller, a second casing surrounding the rear propeller, air trunk means extending 50 from a point adjacent the rear end of the first casing to the second casing and communicating with the latter, and a system of air conduits associated with each plane, open to the atmosphere at various points under 55 the plane and connected to said air trunk means for communication therewith.

4. An aeroplane having in combination front and rear propellers, lateral planes, a casing surrounding the rear propeller, a system 60 of air conduits associated with each plane, open to the atmosphere at various points under the plane and connected to said casing for communication therewith, and a deflector combined with each atmospheric 65 opening of said system of conduits.

5. An aeroplane having in combination a front propulsion propeller, open-ended air trunk means extending from a point immediately in the rear thereof to a point in the rear of the aeroplane, a propeller casing 70 forming a continuation of said air trunk means at the rear thereof, a second propulsion propeller arranged within said propeller casing and means for reversing the rotation of one of said propellers. 75

6. An aeroplane having in combination lateral planes, an air conduit system associated with each plane and open to the atmosphere at various points under the plane and means for causing a circulation of air 80 currents through said air conduit system, said means being reversible whereby said air currents may be caused, at will, to circulate in either direction.

7. An aeroplane having in combination 85 front and rear propellers, lateral planes, an open-ended casing surrounding the front propeller, a second casing surrounding the rear propeller, air trunk means extending from a point adjacent the rear end of the 90 first casing to the second casing and communicating with the latter, a system of air conduits associated with each plane, open to the atmosphere at various points under the plane and connected to said air trunk 95 means for communication therewith and reversing gearing for the rear propeller.

8. An aeroplane having in combination lateral planes, an air conduit system associated with each plane and open to the atmosphere at various points under the plane, means for causing a circulation of air currents through said air conduit system and a group of deflectors arranged at suitable intervals over which the air currents pass externally of the conduit system. 100 105

9. An aeroplane having in combination a front propeller, lateral planes, an air conduit system associated with each plane and open to the atmosphere at various points 110 under the plane, means for causing a circulation of air currents through said air conduit system and a group of deflectors arranged at suitable intervals over which the air currents pass externally of the conduit system, the 115 deflectors being forwardly directed along lines extending from a vertical diameter of said front propeller.

10. An aeroplane having in combination front and rear propellers, lateral planes, 120 reversing gearing for the rear propeller, a casing surrounding the rear propeller air trunk means communicating with said casing and extending from a point immediately in the rear of the front propeller, a system of air conduits associated with each plane, open to the atmosphere at various points under the plane and connected to the air trunk means for communication therewith, a valve controlling the communication 125 130

cation of each conduit system and said air trunk means and a second valve located in advance of the first valve and operable to cut off the forward portion of the air trunk means from the rear portion thereof or to cut off the air trunk means as an entirety from said conduit system.

In testimony whereof I affix my signature in presence of two witnesses.

JOHN R. CAMPBELL.
